UNITED STATES PATENT OFFICE.

AUGUST KRASTIN, OF CLEVELAND, OHIO.

SPEED-GOVERNOR FOR EXPLOSIVE-ENGINES.

SPECIFICATION forming part of Letters Patent No. 674,034, dated May 14, 1901.

Application filed June 14, 1900. Serial No. 20,283. (No model.)

To all whom it may concern:

Be it known that I, AUGUST KRASTIN, a citizen of the United States, residing at Cleveland, in the county of Cuyahoga and State of Ohio, have invented certain new and useful Improvements in Charge-Mixing Apparatus for Explosive-Engines, of which the following is a specification.

My invention relates to improvements in apparatuses designed for feeding the charges for hydrocarbon explosive-engines; and the objects of my improvement are to provide simple, efficient, and easily-manipulatable means for this purpose, which furnish for all condition (loads) the requisite charge thoroughly mixed and of the proper explosive quality. I attain these objects in an apparatus constructed substantially as shown in the accompanying drawings, in which—

10 Figure 1 represents a vertical longitudinal sectional view of such apparatus in connection with the valve end of an explosive-motor cylinder. Fig. 2 represents a cross-sectional view of same on line xx . Fig. 3 is an inner face view of a part thereof detached, and Fig. 4 is a front end view of said apparatus.

15 Like letters of reference denote like parts in the drawings and specification.

In the drawings, A designates the cylinder, B the piston, and C the inlet-valve, of an explosive-engine. The port a leads to its exhaust-valve. (Not shown.)

The charge-supplying contrivance comprises, substantially, the casing D, upon and within which are mounted the barrel E and sleeve F, the piston G, which snugly fits said barrel, and the lever H, which permits the shifting of said sleeve and piston simultaneously.

20 At b the casing D is adapted for connection with the inlet-valve cage I, with which cage the former is arranged in open relation, as shown in Fig. 1. The relative position of casing to valve-cage may vary to suit particular engine constructions without departing from the nature of my invention.

In the fore part of the casing is slidingly arranged the sleeve F. Said sleeve has an internal partition c. Outside of said partition a link d has pivoted connection with said sleeve, which link in turn connects with arm e of lever

H, the latter being pivoted between the brackets ff of casing D, as seen in Figs. 1 and 4.

On top of the sleeve F is provided an arm g, 55 which affords adjustable screw connection with the piston-rod h. In the lower inner side of said sleeve are a plurality of laterally-arranged ports $i i i$, all of which ports may be set in open relation with the opening j of the 60 casing, or by shifting the lever H from the position as shown to that indicated at k and k' one is enabled to set only two or one of said ports in communication with the opening j. Said opening is preferably covered with a 65 screen j' to prevent dust from entering said ports or sleeve. The barrel E is arranged on top of the casing D. A depending portion l of said barrel extends through an opening of 70 said casing into the interior part thereof, as seen in Figs. 1 and 2. The front end of said barrel is provided with a removable plug m to enable insertion of the piston, and inside the plug is an adjustable gland n, screwed up against the packing o for the purpose of establishing a liquid-tight joint for the piston-rod, which has sliding contact in and through 75 said packing. A feed-pipe p intersects with the barrel at or near the plug end, as shown in Fig. 1. In said feed-pipe is provided a needle or stop valve q for control of the flow of 80 the liquid fuel that is conveyed to said barrel.

In the bottom of the barrel (respectively in its depending portion l) there are a plurality of perforations r. Said perforations present 85 such diminutive capacity as to require an actual suction of the main piston in order to establish a flow of liquid through said perforations. Such conditions must necessarily effect a thorough mixture of the liquid fuel 90 with the influx of air.

The barrel E and sleeve F are relatively so positioned or adjusted that the piston exposes 95 as many perforations as a certain influx of air will require in order to effect a properly-proportioned explosive mixture. When air is drawn through all the ports, then the combined capacity (area) of all the perforations is also available to furnish the necessary liquid fuel for a full charge of an explosive mixture. In shifting the lever to a position as indicated at k then the outer port of the sleeve

would be covered by the casing and the inner perforation or perforations of the barrel by the piston G. Thus less air would be drawn in; but also less liquid fuel would be available for such diminished quantum of air, and if the lever is set in a position as indicated at k' then air can only enter through the inner port and liquid fuel only through the outer perforation or perforations, which in this instance would furnish the smallest charge for the cylinder, but yet the same would be composed of the requisite proportions to render it comparatively efficient.

From the foregoing it can readily be understood and seen that by supplying the liquid fuel in finely-subdivided state a thorough mixture of air and fuel can at all times be effected, and by adjusting the air and fuel supply the proper proportions of air and liquid fuel can and will be maintained to furnish an explosive mixture in varying charges.

In the side of the casing and at or near the air-inlet glasses s are inserted to enable ob-

servation of the commingling process of the air with the liquid fuel.

What I claim, and desire to secure by Letters Patent, is--

In explosive-engines the combination with inlet-valve cage of a casing arranged in open relation with said cage, said casing having a side opening, a perforated, partitioned sleeve registering with said opening, a fuel-supply barrel with a perforated portion extending into said casing, a piston located in said barrel and arranged to control the perforations therein and suitable means for moving said sleeve and piston in unison all constructed and arranged substantially as and for the purpose set forth.

In testimony whereof I affix my signature in presence of two witnesses.

AUGUST KRASTIN.
